UNITED STATES PATENT OFFICE.

LEE B. SCHMERBER, OF WILKINSBURG, PENNSYLVANIA, ASSIGNOR TO WESTINGHOUSE ELECTRIC & MANUFACTURING COMPANY, A CORPORATION OF PENNSYLVANIA.

SWIVEL HEAD FOR COIL-PULLING MACHINES.

Application filed March 5, 1923. Serial No. 622,842.

My invention relates to coil-forming machines, such as are employed for the manufacture of coils used in dynamo-electric machines.

5 It is among the objects of this invention to provide an attachment for coil-stretching or forming machines that shall be of simple compact structure, inexpensive to manufacture and that shall be applicable to the standard apparatus now employed.

10 It is a further object of my invention to provide such an attachment that shall be adapted to form the coil in a peculiar manner to adapt it more readily to the machine in which it is to be employed.

15 Coil-forming or stretching machines consist of dies and forms which are movably adjustable to produce certain shapes of coils from simple loops, such as can readily be formed by winding several turns of conductor material on a wooden form. Such forming machines are, however, limited to simple stretching operations and do not provide for the twisting and looping of the conductor 20 members which is essential, as, otherwise, the ends of the coils will interfere with each other in the process of assembling in the armature, stator, or rotor of a dynamo-electric machine.

25 My present invention is directed to a swivel head which is adapted to be mounted on one end or both ends of a coil-stretching machine. The head is provided with a clamp or engaging member adapted to receive the end of a looped coil and the swivel member is so constructed as to automatically twist the end of the coil through a predetermined angle during the coil-stretching operation.

30 In the accompanying drawings constituting a part hereof and in which like reference characters designate like parts,

Figure 1 is a side elevational view of a swivel-head attachment embodying the principle of my invention;

35 Fig. 2 is a front elevational view thereof; Fig. 3 is a top elevational view of a looped conductor member;

Fig. 4 is an elevational view of the coil (Fig. 3) after it has been formed or stretched;

40 Fig. 5 is an end elevational view showing the shape of the end of the coil effected by the swivel attachment, illustrated in Figs. 1 and 2; and

Fig. 6 is a view, partially in cross section, of the swivel head of Fig. 1, taken on the line 55 VI—VI of Fig. 2.

Referring to Figs. 1, 2 and 6, the swivel head comprises a base member 1 having a projecting flange portion 2 by which it is adapted to be secured to the horizontal arm 60 3 of a coil-forming machine (not shown). The swivel 4 comprises an annular member 5, which is secured by screw bolts 6 to a ring 7 rotatably mounted on the base 1 and engaging a shoulder thereof to prevent the 65 member 5 from moving laterally thereon. The swivel member 4 is further provided with a clamping flange 8, which is adapted to secure a chuck 9 or other clamping member for securing a coil 10. A handle 11 is 70 hinged to a projecting lug 12 of the swivel member 5 and is provided with a finger 13 to engage a notch 14 of a rotatable ring 15. Pressure is applied to the finger 13 by a spring plug 16 to force it into engagement 75 with the notched ring 15.

The ring 15 is held in position by a clamp plate 17 secured to the back of the base 1 by screw bolt 6^a, the plate 17 having a projecting portion 18 which is provided with a 80 spring-actuated pawl 19 for engaging notches 20 provided in the ring 15. The ring member 15 is further provided with a stop 22 for the finger 13 of the handle 11 and a plurality of graduations 23 are 85 provided thereon to indicate the amount of adjustment made by the pawl and ratchet 19 and 20, respectively.

The clamping plate 17 is provided with a marking 24 in alignment with the zero position 90 on the ring 15 when the handle 11 is vertical.

The operation of my device is briefly as follows: A wound conductor member 26, comprising a plurality of loops or turns 27, is 95 inserted in the clamp 9 and the side or slot portions 28 are engaged by other members of the coil-forming machine (not shown). The movable parts of the coil-forming machine are then actuated to stretch the coil to 100 the shape illustrated in Fig. 4, which results in one of the coil slot portions 27 being twisted at an angle, and the ends 29 and 30 are looped, as illustrated. The loop 30, as shown in Fig. 5, should be twisted on an 105 angle to facilitate assembling the coils in the

slots of the armature so as to provide the proper clearance between adjacent coils. This twisting is accomplished by the swivel head attachment in the following manner: 3 The angle at which the ends 29 and 30 are to be twisted depends upon the radius at which the coil is mounted and the number of such coils in a given circumference. This angle usually varies within the range of zero 10 to 30 degrees, and the swivel head is adjusted to the desired angle by setting the ratchet pawl 19 in the notch of the ring 15 corresponding to the graduation 23, giving the angle desired. This sets the stop 22 in a 15 certain angular position relative to the finger 13 of the handle 11, which is maintained in its vertical position, as shown. During the coil-stretching operation, the strain applied to the ends of the coil by the longitudinal and 20 lateral stretching automatically rotates the swivel member 4, bringing the stop finger 13 against the stop 22, resulting in the proper twist or angle on the ends 29 and 30 of the coils 10, as shown.

25 It will be readily understood, from the above description of my invention, that a swivel attachment on a coil-forming machine, such as illustrated herein, provides a simple and efficient means of forming the 30 exact shape of coil to meet the requirements in the manufacture of dynamo-electric machines. Another advantage of this device is that, by twisting the ends of the coil, the length of the entire coil is materially shortened, thereby saving in the amount of copper employed.

Although I have described a specific embodiment of my invention, it will be obvious to those skilled in the art that various changes 40 may be made in the details of construction without departing from the principles herein set forth. For instance, the details of my mechanism may be varied in design in various ways as to the kind and number of its 45 parts without varying the function herein described.

I claim as my invention:—

1. A swivel head for a coil-forming machine comprising a base member, a swivel member rotatably mounted thereon, means on 50 said swivel member for engaging a coil to be formed, a finger on said swivel member and

an adjustable stop member on said base member for engaging said finger.

2. A swivel head for a coil-forming machine comprising a base member, a swivel member rotatably mounted thereon, means on said swivel member for engaging a coil to be formed, a finger pivotally mounted on the swivel member and a stop on said base member for engaging said finger. 55 60

3. A swivel head for a coil-forming machine comprising a base member, a swivel member rotatably mounted thereon, means on said swivel member for engaging a coil to be formed, a ring member revolvably mounted on the base member, a stop on said ring member for engaging the finger on the swivel member and means for adjusting the angular position of said ring member relative to said base member. 65 70

4. A swivel head for a coil-forming machine, comprising an annular base, a swivel member rotatably mounted thereon, a finger on said swivel member, a rotatable disk provided with a stop for engaging said finger mounted on said base, said swivel member being adapted to be actuated in an angular direction relative to said base and stop. 75

5. A swivel head for a coil-forming machine, comprising a base, a swivel clamp angularly movable thereon, a stop comprising a handle hinged on said swivel clamp, a ring provided with a plurality of notches having a recess adapted to receive the handle stop 80 of said swivel clamp rotatably mounted on said base, and a disk provided with a spring pawl fixed on said base, said pawl being adapted to fit into the notches of said ring. 85

6. A swivel head for a coil-forming machine comprising a swivel clamp, a base for supporting the swivel clamp, a ring having a projecting finger rotatably mounted on the base for securing the swivel clamp, a movable stop for engaging the finger provided with graduated notches mounted on the base and a locking plate provided with a spring pawl for engaging said notches secured to the base. 90 95

In testimony whereof I have hereunto subscribed my name this 21st day of February, 1923. 100

LEE B. SCHMERBER.
